UNITED STATES PATENT OFFICE

ANTONIO BENITEZ, OF CRISTO, CUBA

CULTIVATING MACHINE

Application filed May 28, 1930, Serial No. 456,690, and in Cuba April 28, 1930.

This invention relates to improvements in cultivating machines, the object of the invention being to provide an improved machine of this kind which is simple in construction, is strong and durable, is adjustable in width to accommodate itself to the width of spaces between the rows of growing crops and which is not likely to get out of order.

With the above and other objects in view, the invention consists in the construction, combination and arrangement of devices hereinafter described and claimed.

The invention is described with reference to the figures of the annexed drawings, of which

Fig. 1 is a plan of a cultivating machine constructed in accordance with this invention.

Fig. 2 is a side elevation of the same.

Fig. 3 is a detail side elevation of the rear portion of the supporting frame of the machine.

Fig. 4 is a detail side elevation of a share and the supporting arm carrying it.

Fig. 5 is a horizontal section on line 5—5 of Fig. 4.

Fig. 6 is a vertical transverse cross section on line x—x of Fig. 1.

Fig. 7 is a horizontal section on line z—z of Fig. 2.

Fig. 8 is a perspective of the mounting of one of the lateral pieces supporting the outer side shares with the adjustable arm connecting it to a central supporting piece controlling the width of the machine.

My improved cultivating machine comprises a frame which is composed of two lateral bars C joined by a rear bolster C', the front end portions of the lateral bars C being slightly bent inwardly and each having a longitudinal slot a. A longitudinal central bar B has its rear end bent at right angles and secured by means of a pair of bolts b to the rear bolster C' and its front end has an upwardly directed hook B' in the end portion of which is pivotally mounted a ring H for the attachment of a draft animal, said bar B extending at its forward portion through an attaching member

formed by two horizontal oval plates E having studs e on their opposing sides, the two horizontal plates E being secured together by a pair of bolts e' which extend through openings therein at points on opposite sides of the central bar B. The pairs of opposed studs e arranged in vertical alignment form pivot pins for two lateral bars D the front ends of which form eyes for pivotally mounting the said bars on the studs e and the front half of each lateral bar D has approximately the shape of a quarter of circle and is adjustably connected to the front end of one of the lateral bars C by means of a pair of bolts d passing through the slot a of said lateral bar. The rear half of each lateral bar D has an outwardly bent extension the rear portion of which is substantially parallel to and spaced from one of the lateral bars C.

At a downwardly bent portion of the longitudinal central bar B connecting the hook B' to said bar B are secured by means of bolts, two hanging brackets F provided with a series of openings to permit adjustment of their position relatively to the central bar B, and in bearings at the ends of said brackets there is rotatably mounted the shaft of a guiding wheel G, which bears upon the ground and is made of a single steel casting piece and has thick spokes.

The frame carries five shares L one of which is supported by a hanging bracket K secured by means of bolts to the central bar B at a point in front of the connections of the bars D to the bars C; two being supported by hanging brackets K secured by means of bolts to the rear ends of the lateral bars C, and the others being supported by hanging brackets secured by means of bolts to the end portions of the angle extensions of the lateral bars D. For adjusting the width of the apparatus, that is, to say, the distance of the outer lateral shares L to the central bar B, the latter is provided about its middle portion between the element E and the bolster C', with two lateral members I provided at their opposed ends with vertical flanges secured to the central bar B by means of bolts i. The curved

portion of each member I has an opening through which passes a bolt which serves to fix to the same a connecting arm J which is provided with a series of openings to enable an adjustable connection of said arm to be effected to the members I. The other end of each arm J is pivotally connected by means of a bolt to a square piece M which by its vertical portion is secured to one side 10 of the bracket K of the corresponding outer side share L by means of the same bolts which secure said bracket K to the extension of the associated lateral bar D.

Behind the point of attachment of the central forward share L on the central bar B front ends of plough handles A are attached, as at a'. The said plough handles are connected together by a horizontal transverse brace P, and each of the plough 20 handles is connected by a connecting bar O at a point near its center to the adjacent lateral bar C; and through another similar connecting bar N each of the plough handles is connected to the member I of the same 25 side through the same bolt which secures to the latter piece the connecting bar J. The plough handles A are hence effectually braced.

The outer shares L mounted on the extensions of the lateral bars D can be opened to a space of about 52 inches between them and closed to about 30 inches, according to the width of the spaces between the rows. To effect such adjustment it will be only 30 necessary to change the pivotal connection point of each one of the connecting bars J to the member I at the same side, and to laterally adjust the members D, as will be 35 understood.

40 What I claim is:

A cultivator having a frame comprising a pair of side bars having inwardly curved front ends, a rear cross bar connecting the side bars, a center bar secured to and extending forwardly from the rear cross bar, and attaching member adjustable longitudinally on the center bar, lateral bars on the outer sides of the side bars having curved intermediate portions longitudinally adjustably secured to the curved front ends of the side bars and having their front ends pivotally connected to the said adjustable attaching member, said side bars, center bar and lateral bars having means for the attachment of cultivator blades thereto, attaching members secured to and extending laterally from opposite sides of the center bar, and connecting arms secured to the lateral bars and adjustably secured to said attaching members.

In witness whereof I affix my signature.
ANTONIO BENITEZ.
